(No Model.)

I. L. HYDE & C. H. JONES.

SECTIONAL LADDER.

No. 374,154.

Patented Nov. 29, 1887.

UNITED STATES PATENT OFFICE.

IRA L. HYDE AND CLARENCE H. JONES, OF CHAZY, NEW YORK; SAID HYDE ASSIGNOR TO SAID JONES.

SECTIONAL LADDER.

SPECIFICATION forming part of Letters Patent No. 374,154, dated November 29, 1887.

Application filed October 5, 1886. Serial No. 215,387. (No model.)

To all whom it may concern:

Be it known that we, IRA L. HYDE and CLARENCE H. JONES, citizens of the United States, residing at Chazy, in the county of Clinton and State of New York, have invented a new and useful Improvement in Sectional Ladders, of which the following is so full, clear, and exact a description as will enable others skilled in the art to which our invention applies to make and use the same, reference being had to the accompanying drawings, in which—

Figure 1 is a front elevation of our improved ladder, showing the two sections locked firmly in position. Fig. 2 is a side elevation of the same, showing the rounds in cross-section. Fig. 3 is a front elevation of a part of our sectional ladder, showing a portion broken away around the pivotal points of the locking-pin. Fig. 4 is a detail view of one of the folding arms. Fig. 5 is a side view of a portion of one of the sections. Fig. 6 is a detail view of the locking-round. Fig. 7 shows the upper section of our sectional ladder provided with a hook. Fig. 8 is a front elevation of the same. Figs. 9 and 10 are modifications showing the slot in the folding splice-pieces extending in opposite directions.

The object of our invention is to provide a ladder in sections which may be readily and quickly secured together to convert the several sections into a long ladder.

Another object of our invention is to construct a ladder which, when it is put up, will not be likely to become accidentally separated where the sections are joined together. Another object of our invention is to provide the splice-pieces with means for preventing them from being forced too far toward the center, and thus accidentally broken off.

The objects generally of our invention are to construct a complete and practical sectional ladder; and the invention consists in the construction, combination, and arrangement of parts, as will be hereinafter fully explained, and particularly pointed out in the claims at the end of the specification.

The main side pieces are designated by the letters A A, each of which is provided with the splice-pieces B B, having the recesses B' in

their outer free ends. These pieces are pivoted loosely at b to the round which comes next the top in the section to which the splice-pieces are pivoted.

Each of the splice-pieces B B is provided with a pin, b', which is adapted to engage with the recesses c and c' in the main sides of the ladder, respectively.

The locking-round C is provided with an extension, C', which extends off to one side of the central line of the locking-pin, as is clearly shown in Figs. 3 and 6.

Each of the splice-pieces B B is provided with a slot, D, through which the locking-round works during the operation of detaching the sections from each other, when it is desired to take the ladder to pieces. At the upper end of one of the sections we provide a hook, E, which is adapted to extend over the weather-boards on the top of the building when the ladder is used on a roof.

In order to prevent accidental displacement of the locking-round C, we provide a wedge, F, which is secured to the side of the ladder by a chain, f. This wedge is adapted to be inserted in the slot D, just above the extended portion C' of the locking-round C, after the locking-round has been turned round in a position to lock the sections together. X X designates the point where the ends of the main sections of the ladder meet.

In Figs. 9 and 10 we show modifications of the splice-pieces B, and show the slots extending at an angle to the line of the sides of the splice-pieces, so that the liability of accidental displacement of the splice-pieces will be greatly lessened.

The operation of our device is as follows: When it is desired to place the ladder in position for use, the splice-pieces are pressed toward the main sections until the pins b' b' engage firmly with the recesses c and c' on the main sections. The locking-key is next turned around until the extension C' faces the round of the ladder to which the splice-pieces are pivoted, and the wedge F being fitted into the slot D the device is locked firmly in position against accidental displacement. When it is desired to unlock the sections, the wedge F is taken out and the locking-key turned around

until the extension C' on the same faces the pins b' b', when the splice-pieces can be disengaged from the recesses c and c' by slipping the splice-pieces toward each other through the 5 medium of the slot D.

We are aware that it is not broadly new to make a ladder in folding sections, and we therefore disclaim such construction, broadly; neither do we wish to be understood as claiming, broadly, an extension-ladder having slotted 10 splice-pieces and pins for connecting them with the stile of the next adjacent section, and an enlarged round-carrying or key piece, which locks the splice-pieces into engagement 15 with the stiles, and the stops on one of the rounds of the section to which the spliced pieces are pivoted; but we are not aware that a ladder has been constructed similar to ours, and

What we therefore desire to secure by Letters 20 Patent, and what we therefore claim, is—

1. The combination of the sections, the splice-pieces, and the locking-round with the wedge for holding the locking-round in position, substantially as described.

2. The combination of the sections provided with the splice-pieces and with the locking-round, the wedge, and the chain, substantially as described.

In testimony that we claim the above we 30 hereunto set our hands and affix our seals in the presence of two subscribing witnesses.

IRA L. HYDE. [L. S.]
CLARENCE H. JONES. [L. S.]

Witnesses:

I. W. HUBBELL,
J. S. JONES.
